UNITED STATES PATENT OFFICE.

HARRY GEO. TELLING, OF LONDON, ENGLAND, ASSIGNOR TO ADAPTABLE CODE CONDENSERS LIMITED, OF LONDON, ENGLAND, A COMPANY OF GREAT BRITAIN.

MECHANICAL CODING AND DECODING OR CIPHERING APPARATUS.

Application filed January 5, 1921. Serial No. 435,199.

To all whom it may concern:

Be it known that I, HARRY GEORGE TELLING, a subject of the King of Great Britain, residing at 105 Como Road, Forest Hill, 5 London, England, have invented certain new and useful Improvements in or Relating to Mechanical Coding and Decoding or Ciphering Apparatus, of which the following is a specification.

10 This invention relates to mechanical coding and decoding or ciphering apparatus and has for its chief object to provide an apparatus for rapidly and accurately converting or transforming groups, sets or 15 series of figures representing messages or phrases according to known methods into polysyllabic pronounceable code words, each word produced having at least a two-letter difference from every other word capable 20 of being built up by or produced by the apparatus, and also for decoding such words by converting them back to the original group or set of figures.

Hitherto known methods, for converting 25 messages expressed by groups of figures into pronounceable code words fulfilling the requirements of the rules and regulations of the International Telegraphic Convention, and for checking the accuracy of words so 30 formed and vice versa, have necessitated calculation on the part of both sender and receiver, whereby considerable time is occupied and the likelihood of inaccuracy and 35 error is present; whereas according to the present invention the whole operation of conversion or transformation in either direction is performed rapidly, automatically and accurately, the complete code word being exhibited or exposed to view simultaneously 40 with and beside the corresponding figures thus facilitating checking, and eliminating liability of error.

The apparatus according to the present invention comprises a series of movable units 45 in the form of tables, plates, drums or other members, in accordance with the number of syllables in the code word, such members being adapted to be variably locked or coupled for conjoint movement by suitable 50 gearing while another member or other members remains or remain stationary or all the members may be moved together, and

in conjunction with these movable members there is employed an indicator or guide which, in being set to indicate or determine 55 the base or foundation of the word to be formed, shuts off or cuts out such of the movable units or sections thereof as will not be required for the formation of the particular word.

60 Each movable unit represents one syllable of the word and the units are moved as required by a handle, or the equivalent thereof and there is provided a gearing operated by a separate handle or the like or it may be operated by the movements of the unit-moving handle to couple the preceding 65 syllable forming units separately and in succession with final syllable-forming unit.

Each unit is furnished with two series of 70 biliteral symbols, each pair of symbols being accompanied by a pair of figures all arranged on a definite plan or system. Each symbol is composed of a vowel and a consonant, the vowel in some cases preceding 75 the consonant and in others being preceded by the consonant. The arrangement of symbols on all the movable units is the same and the arrangement of figures on all the units, with the exception of that for the final syllable is the same. The unit for the final 80 syllable is furnished only with symbols, the figures being placed on a stationary member beside the unit.

In combination or co-operation with the 85 gearing, there is a catch which is released only when the final syllable is reached thus enabling all the units to be rotated together so that should a message have been mutilated in transit the user of the machine can 90 manipulate the units together, check the error and find out and readily determine the correct and only possible combination.

Referring to the accompanying drawings:—

95 Fig. 1 is a top plan view of an apparatus embodying or constructed in accordance with the present invention.

Fig. 2 is a plan with the cover removed.

Fig. 3 is an end elevation of Fig. 1.

Fig. 4 is a view of one of the parts of the apparatus.

Figure 5 is a view of the gearing taken on the line 5—5 of Figure 1, and

Figure 6 is a view of the gearing from the opposite end being taken on the line 6-6 of Figure 1.

The form of apparatus, chosen for illustrating an embodiment of the present invention is designed and arranged to deal with messages employing words of three syllables or figure groups each word comprising six figures.

10 A, B and C. are the three movable units. D is the movable indicator, E is the coupling mechanism, F is the casing and G the operating mechanism.

15 The members A, B and C. in the present embodiment of the invention are conveniently in the form of rotary drums or cylinders arranged on horizontal shafts *a*, *b* and *c* respectively, these shafts being carried in suitable bearings in the frame or 20 casing F of the apparatus.

The movable units A, B and C. are conveniently arranged within the casing F which is provided with a lid or cover F' and in this lid are formed three windows 25 or openings f, f', f'' large enough to show, in the case of units A and B a horizontal row of letter and figure groups, one group in each column and in the case of unit C one row of letter group, one group in each 30 column.

35 The units A and B are each provided with two series of letter groups, each representing a biliteral syllable, in one series the syllables begin with a vowel and in the other with a consonant. Each two-letter group is accompanied by a two figure group, all arranged preferably on the following plan.

In the first five columns of biliteral groups or syllables a vowel precedes a consonant, 40 the same vowel being employed throughout a column and different vowel to each column. Each biliteral group is accompanied by two figures running successively throughout the five columns from 00 to 99. In the remaining five columns a consonant precedes a vowel and a separate vowel is employed in each column. In the second five columns the figures are arranged as in the first five columns. These two series are mounted upon 45 the same units A or B, as both series are to form the same syllable of the code or other word, and therefore can be moved together or need not be moved separately, but each series of five columns may be mounted upon 50 a separate unit.

55 In the arrangement illustrated, the unit A is employed for the first syllable of the word, and the unit B for the second or intermediate syllable, as the apparatus as constructed is intended for three syllable words or words containing six letters. If four syllable words are required, an additional intermediate syllable unit will be added.

The unit C is used in connection with the 60 final syllable of the word. The unit C or

final syllable unit is preferably provided with letter groups only, and these are

arranged on the plan above described. Alongside the opening f' in the top or lid F' of the casing F, through which the required combination of letters on the unit C are shown are arranged figures running from 0 to 9 as shown at C' (Fig. 1) one figure being employed for each column of syllables on the unit C.

Each syllable of a word begins with a vowel or a consonant and each syllable contains a vowel and a consonant thus the possible combinations for the first two syllables are (a) both syllables commencing with a vowel (b) the first syllable commencing with a vowel and the second with a consonant (c) the first syllable commencing with a consonant and the second with a vowel and (d) both syllables commencing with a consonant.

According to the present invention when a group of figures is to be converted into a code word the first figure in a group is used to determine the basic formation of the word to be produced and conveniently on the following plan, for the above mentioned four combinations for the first two syllables. When the group begins with a cipher or figure 0 then the basic formation of the word will be both syllables beginning with a vowel.

120

125

130

When the first figure of the group is 1, then the basic formation will be first syllable beginning with a vowel and the second with a consonant. When the first figure is 2 then the basic formation will be first syllable commencing with a consonant and the second with a vowel. When the first figure is 3 then the basic formation of the word will be both syllables commencing with consonants.

While this system for determining the basic formation of a code word can readily be memorized, means are provided in accordance with this invention to minimize the liability to error which would arise if the user of the apparatus had to rely on memory, and by the means provided, it is ensured that only the portions of the units required for forming the first and second syllables of the words are visible when the apparatus is being used. A convenient embodiment of the means employed for this purpose comprises a slide D arranged to be moved between the units A and B and the opening f' in the cover F through which portions of these units are visible. The slide D has openings d, d', d'', d'', d⁴, d⁵, (see Fig. 4) and is preferably provided with a visible indicator comprising the numerals 0, 1, 2, 3 accompanied by letter combinations V.V.V.C. C.V. and C.C. The figure 0 indicates the first basic formation in which both syllables commence with a vowel and therefore is accompanied by the letters V—V indicating vowel. These figures and letter combinations are visible in turn through openings f³, f⁴ in the lid F. When the figure 0 is visible in the opening f² and the letters V V are visible in the opening f³ the slide D is in such a position that the second series of groups on the unit A is invisible and only the first group can be seen through the opening d which coincides now with the opening f in the lid F. In this position of the slide D also, the second series of groups on the unit B are invisible while the first series thereon are visible since the opening d² in the slide coincides with the opening f' in the lid.

Similarly if the first figure of the group is 1, the slide D is moved until the figure 1 appears in the opening f³ when the letters V. C. will be visible in the opening f⁴. In this position of the slide the first series of groups on the unit A will still be visible through the opening d since the first syllable is commenced with a vowel, but the first series of groups on the unit B will now be cut out and the second or consonant vowel series will be visible through the opening d³ which now coincides with the opening f'. When the group begins with the Figure 2 indicating the C.V. combination, the first syllable of the word beginning with a consonant and the second with a vowel, then the second series of groups on unit A will be visible through

the opening d' and the first series of groups on the unit B will be visible through the opening d⁴. When the group begins with the Figure 3, indicating both syllables to begin with a consonant, then the second series on the unit A will still be visible through the opening d' and the second series on the unit 3 will be visible through the opening d⁵.

The slide D is arranged to move in suitable guides carried on the underside of the lid F and is also provided with a rack D' which projects into an opening in the lid. It is necessary to prevent the slide D from being accidentally displaced when the apparatus is being operated and for this purpose the idle gear wheel D² gears with the rack and acts as a spring detent and tends to prevent the slide D from moving accidentally after being set.

In accordance with the present invention, as above stated, each of the units A and B are successively coupled with or moved separately in conjunction with the final unit C which latter therefore is moved an extent equal to the combined movement of the units A B.

A convenient gearing for ensuring this proper movement, comprises a handle or knob G mounted upon a vertical shaft g which carries a bevel gear wheel G' arranged to gear with a bevel wheel G² on the shaft c of the unit C. Mounted on the shaft c is a gear wheel G³ which gears permanently with a wheel G⁴ carried on a shaft g'. In the initial position of the gear the wheel G⁴ rotates a wheel G⁵ on the shaft a of the unit A through an idler wheel G²⁰ on a shaft g²⁰ so that when the knob G is rotated the units A and C rotate together.

The shaft g' is adapted to be moved longitudinally being mounted to slide in suitable bearings in the ends of the casing. On this shaft g' is also mounted a gear wheel G⁶ which in the initial position (see Fig. 2) is idle, but when the shaft is moved longitudinally to the right this wheel G⁶ is brought into mesh with a wheel G⁷ on the shaft c, and with an idle wheel G²¹ on the shaft G²⁰, this idle wheel gearing with a wheel G¹⁰ on the shaft b of the unit B. In this second position the wheel G⁴ is moved out of gear with the wheel G²⁰ so that when the knob G is rotated, the units B and C being connected by the wheel G⁶ these two units will rotate together.

When it is required in checking purposes or for detecting mutilations, and correcting, to rotate all units together, the shaft g' is moved longitudinally still further to the right, in which position a wheel G⁸ on the shaft g' moves into mesh with the wheel G²⁰ on shaft a and the wheel G³ on shaft c. In this position the wheel G⁶ is still in mesh with the wheel G⁷.

Mounted above the shaft g' is a shaft g^2 which is arranged to move longitudinally in company with the shaft g' . In the first and second positions of the gear the shaft g^2 is prevented from rotating by a catch H which is mounted upon one end of the shaft and engages an opening f^{10} in the end of the casting. When the shaft g^2 is moved longitudinally into the third position of the gear, the catch H is moved out of the opening f^{10} and the shaft is free to rotate.

On this shaft g^2 is a gear wheel G^9 which in the first position of the gear meshes with the wheel G^{21} on the shaft of the unit B and as the shaft g^2 cannot rotate the unit B is locked against movement. As the gear is moved into the second position, the gear wheel G^9 is moved out of mesh with the gear G^{21} and another wheel G^{11} on the shaft g^2 is moved into mesh with the wheel G^{20} of unit A thus locking the unit A against rotation while the unit B is coupled with the unit C. When the gear is in the third position, the wheel G^{11} is still in mesh with the wheel G^{20} and another wheel G^{12} on the shaft g^2 is in gear with the wheel G^{21} of unit B, but in this position, as already stated, the shaft g^2 is free to rotate so that the units A, B and C are free to be rotated in company by the gearing already described.

A convenient mechanism for moving the shafts g' , g^2 longitudinally comprises a worm or screw H' which passes through a threaded opening in a block H^2 which is secured to the left hand ends of the shafts g' , g^2 . This worm is conveniently rotated by a disc wheel E provided with a spring catch H^4 arranged to engage notches H^5 on the wheel.

The openings f , f' , f^2 through which the readings are taken are preferably provided with sliding shutters A^{10} , B^{10} , C^{10} respectively, having openings sufficiently large to enclose the required group thus providing a ready means for easily reading the entire groups.

In operation, if for example the group of figures is 0, 00, 13, 3, to transform this into a word, the initial figure 0 reading from left to right is taken, this figure determines the basic formation of the word, the slide D is moved until 0 thereon shows in the opening f^3 and the letters V V in the opening f^4 denoting that the first and second syllables are to commence with vowels. The slide D in this position closes portions of the openings f and f' so that only the units A and B showing vowel consonant groups are visible. The next two figures 00 are then taken and the gearing rotated moving the units A and C until 00 the figures on unit A appears in the opening f . Beside the figures 00 on unit A will be found the letters A B, giving the first syllable of the word, the coupling gear 65 is now moved to connect units B and C, then

the next two figures 13 are taken and the units B and C rotated until the figures 13 appear in the opening f' . Along with the figures 13 on unit B will be found the letters A S, giving the second syllable of the word. To find the third syllable, the last or right hand figure of the group is taken. This figure in the present example is 3 denoting the third column on unit C and without further operation of the gearing the group of letters on unit C opposite the figure 3 of the indicator C' is I N. Thus from the group of figures 0.00.13.3 we have the word ABASIN having a vowel consonant formation for the first two syllables as denoted by the initial figure 0.

When a word is to be decoded or transformed into a group of figures, the word is first examined as to its basic formation assuming that it is the word ACINOC. The first and second syllables begin with vowels, the basic formation is therefore V—V. This is the 1st combination (see guide D Figure 4) and therefore the first figure will be 0. The first and second units A and B are then rotated until the letters A C appear on unit A and associated with the letters A C the figures 01 will appear in the opening f . The units B C are next rotated until the letters I N appear on unit B. With these letters I N are to be found the figures 48. Without further operation the final syllable O C should be shown by the unit C and should appear in column 4 giving the final figure 4 and the complete group is 00.01.48.4.

As above stated it is an essential feature of this invention that it secures accuracy and eliminates error in that it provides a ready means for detecting and correcting mutilations in a message. For instance in the above quoted example the final syllable of the word should appear on unit C simultaneously with the setting of the unit B for the second syllable, if therefore, when unit B discloses the letters I N together with the corresponding figure group, the final syllable O C, does not show on unit C without further operation of the cylinders, then the user knows that there is some mutilation in the message. The unit C thus acts as a check unit and ensures accuracy since by turning this unit in the case of a mutilation, and rotating the other units with it by moving the gear to the third position, the possible variations in the word can be ascertained, whether they occur in the first, intermediate or final syllable, and the code to which the word required belongs being known, the proper word can quickly be ascertained.

As above stated each word capable of being produced has at least a two letter difference from any other word capable of being built up by the apparatus. While a word 130

containing the syllable E T differs actually by two letters from a word containing in the same syllable the letters T E, yet the system employed with this invention cuts out two letter differences which are really transpositions. By referring to the table above it will be seen that in any line of groups on a unit the arrangement of vowel consonant and consonant vowel syllables, a particular figure group say 33 in the vowel consonant combination is accompanied by the letters E T, whereas on the same line in the consonant vowel groups, the syllable figures 33 are accompanied by the letters V E not T E, thus it is ensured that a two letter difference in all words will be obtained without using transpositions.

The apparatus also provides a ready means for secret coding. The units while all being arranged on the same basic formation of letter groups, may have their zero positions varied separately—so that to decipher a message correctly, the particular arrangement of units must be known previously to sender and receiver. Also by providing various zero positions for the catch H, the message can only be decoded correctly by one knowing the correct initial positions of the units.

The invention has been described as embodied in an apparatus for dealing with words of six letters or three syllables chiefly because this is sufficient for most if not all commercial purposes, but the invention is not to be restricted to such an arrangement as an additional intermediate syllable unit can be added but in all cases the final unit will be moved a distance equal to the added amount of all the other units so as to preserve its function of checking and correcting mutilations.

What I claim as my invention and desire to secure by Letters Patent is:—

1. In a mechanical coding and decoding or ciphering apparatus, the combination of a series of movable units representing respectively initial, intermediate and final word syllables or figure groups and adjustable gearing for coupling the initial and intermediate units separately with the final unit.

2. In a mechanical coding and decoding or ciphering apparatus the combination of a series of movable units representing initial, intermediate and final groups and adjustable gearing for coupling the initial and intermediate units in succession with the final unit.

3. In a mechanical coding and decoding or ciphering apparatus the combination with a series of separately movable units represent-

ing initial and intermediate groups of a combined checking and final group unit and means whereby the checking unit is moved in conjunction with all the other units for detecting and correcting mutilations.

4. In a mechanical coding and decoding or ciphering apparatus the combination with initial and intermediate units furnished with figure groups and biliteral letter groups arranged on a plan to ensure a two letter difference between any two words and a final unit having similar letter groups with a figure group, of mechanism for coupling the initial and intermediate units separately with the final unit and mechanism for moving the units for the time being coupled together.

5. In a mechanical coding and decoding or ciphering apparatus the combination with initial and intermediate units furnished with figure groups and biliteral letter groups arranged on a plan to ensure a two letter difference between all words and a final unit have similar letter groups, of a column indicator for the final unit, mechanism for coupling this initial and intermediate unit separately with the final unit and mechanism for simultaneously moving the units coupled together.

6. In a mechanical coding and decoding or ciphering apparatus the combination with a series of movable units having biliteral groups arranged in columns giving separate series of vowel consonant and consonant vowel combinations of a combined indicator and guide for the formation of the desired combination.

7. In a mechanical coding and decoding or ciphering apparatus the combination with movable units bearing series of biliteral groups representing initial intermediate and final syllables or groups and gearing for coupling the initial and intermediate units separately with the final unit of mechanism for locking the units out of use and mechanism for releasing the locking mechanism and for coupling all the units, together.

8. In a mechanical coding and decoding or ciphering apparatus, in combination, a series of separate movable units, representing initial, intermediate and final units, means for coupling the initial and intermediate units with the final units, a locking mechanism for preventing improper movements of the units, means for operating the units coupled together, a combination guide and indicator, a zero indicator and means for adjusting the zero indicator.

HARRY GEO. TELLING.
